CLAIM

The ornamental design for a pair of earphones as shown and described.

DESCRIPTION

FIG. 1 is a front, right, and top perspective view of the right earphone of a pair of earphones showing the new design, shown separately for ease of illustration;

FIG. 2 is a rear, left and bottom perspective view of the Right earphone of a pair of earphones in FIG. 1.

FIG. 3 is a front elevation view of the Right earphone of FIG. 1.

FIG. 4 is a rear elevation view of the Right earphone of FIG. 1.

FIG. 5 is a left side elevation view of the Right earphone of FIG. 1.

FIG. 6 is a right side elevation view of the Right earphone of FIG. 1.

FIG. 7 is a top plan view of the Right earphone of FIG. 1.

FIG. 8 is a bottom plan view of the Right earphone of FIG. 1.

FIG. 9 is a front, right, and top perspective view of the left earphone of a pair of earphones showing the new design, shown separately for ease of illustration;

FIG. 10 is a rear, left and bottom perspective view of the left earphone of a pair of earphones in FIG. 9.

FIG. 11 is a front elevation view of the left earphone of FIG. 9.

FIG. 12 is a rear elevation view of the left earphone of FIG. 9.

FIG. 13 is a left side elevation view of the left earphone of FIG. 9.

FIG. 14 is a right side elevation view of the left earphone of FIG. 9.

FIG. 15 is a top plan view of the left earphone of FIG. 9; and, FIG. 16 is a bottom plan view of the left earphone of FIG. 9.

The broken lines depict portions of a pair of earphones that form no part of the claimed design.

1 Claim, 16 Drawing Sheets
